BRONSON BARLOW, OF CHICAGO, ILLINOIS.

PNEUMATIC WELL FOR INK AND MUCILAGE.

1,186,369.

Specification of Letters Patent.

Patented June 6, 1916.

Application filed October 26, 1915. Serial No. 57,978.

To all whom it may concern:

Be it known that I, BRONSON BARLOW, a citizen of the United States, and a resident of Chicago, in the county of Cook and State 5 of Illinois, have invented a new and Improved Pneumatic Well for Ink and Mucilage, of which the following is a full, clear, and exact description.

My invention relates to an ink well or 10 mucilage well adapted to be employed in connection with ink bottles or mucilage bottles of standard makes and utilizing the said ink bottle or the mucilage bottle as a reservoir.

15 The object of my invention is to improve a well of the indicated character improved in various particulars and having special advantages which will be stated in connection with the description of the novel construction characterizing the practical embodiment of my invention.

Reference is to be had to the accompanying drawings forming a part of this specification in which similar reference characters indicate corresponding parts in all the views.

Figure 1 is a longitudinal vertical section of an ink well embodying my invention showing the same in use; Fig. 2 is a plan view, the bottle being omitted; Fig. 3 is a transverse vertical section; Fig. 4 is a plan view, illustrating a slight modification; and Fig. 5 is a side view of the ink well shown in Fig. 4.

35 The bottle 10, illustrated, is of a form in general use for ink and mucilage, being provided with a neck 11, and an annular lip 11^a, on the neck.

My improved stand 12, is rectangular 40 as illustrated in Figs. 1 to 3, to better conform in its general appearance to square bottles. The stand 12, is made of pressed glass, metal, or other suitable material, and may have interrupted ribs 13 at the under- 45 side, providing feet for the stand. The top of the stand 12, presents side surfaces 14, a front surface 15, and a rear surface 16, that slope inwardly from the outer margins toward two depressions, there being a

50 deeper front depression 17, and a shallower depression 18, rearward of the depression 17. The depression 18, is circular to conform to and receive the lip 11^a, of the bottle in the inverted position. A vertical 55 projection 19, rises within the depression 18, and is adapted to be received in the inverted

neck 11, and constitute a stopper therefor. The vertical projection 19, is formed with a vertical groove 20, preferably, V-shaped, extending from the top thereof, and cutting 60 the circular depression 18, and extending to the deeper front depression 17.

With a stand formed as described, to use the same, with a bottle 10, as a reservoir, the stand is inverted and placed on top of the 65 bottle with the stopper projection 19, in the said neck. The bottle is now inverted so that the depression 18, forms a seat for the lip 11^a. The ink will now flow into the well 17, through the notch 20, air entering the 70 bottle as the ink or mucilage exudes therefrom until the ink or mucilage rises in the well 17, to a level to constitute a liquid-seal for the bottle neck, after which no more ink or mucilage will flow to the depression 75 17 except as the level therein is lowered as the ink or mucilage is used so that a constant level is maintained. When the ink or mucilage is all used up, the empty bottle is removed and a new one placed in position. 80

By the described arrangement my improved well has various important advantages. The pen point may rest in the ink so that a pen in frequent use may be kept during intervals of disuse with the point 85 submerged as many writers desire, the pen point resting against the underside of the lip 11^a, of the bottle 10, and the pen-holder ranging across an edge of the stand. When so positioned, the pen can never go deep 90 into the ink. The arrangement of the depressions maintains the ink always pen-deep. In practice, the difference in level between the lip of the bottle neck and the bottom of the reservoir 17, is made pen- 95 deep so that the pen can be dipped without particular attention and with full security, the user knowing that he cannot dip the pen nib or the forward end of the pen-holder into the ink and soil his fingers, and 100 also with the assurance that the pen will not be overcharged and drip nor undercharged to soon run dry. Furthermore, the ink does not evaporate rapidly.

The surface of the pool of ink in the depression 17, is limited by the horizontal section of the said depression at the level of the mouth of the bottle and can be made as small as desired, thus diminishing evaporation. Again, the pen is guided to the ink. 105 The deep depression 17, having the ink pool 110 has a very wide front or mouth, practically

four or five times as wide as the mouth of an ordinary ink bottle. Moreover, the sides of the depression are rounded and sloping from the edge to the bottom of the pool, and 5 guide the pen into the ink, regardless of the direction or angle from which the pen is directed. In this way different people may dip their pens at the same time into the ink well without interference, this being desirable 10 where writing materials are provided in public places, as in a post-office or a hotel, and is a convenience not incident to the common form of ink bottle which admits of only one pen being dipped at a time. 15 It will be obvious, also, that the stand may be easily and thoroughly cleaned. As the ink remains at a constant level, it never dries on the surface of the glass unless it be on a narrow line at the surface. It will be 20 apparent also, that the ink well is stable against being overturned. In the case of mucilage, if the flow should not be sufficiently free, pumping action can be effected by raising and lowering the bottle on the 25 projection 19. In practice, the dimensions of the parts including the projection 19, are such that the stand will be usable only for one standard make of bottle so that a manufacturer can be assured that his stand will 30 not likely be employed in connection with other bottlers of similar goods. As the stand is made in a single piece, it can be produced very cheaply and for the same reason, is very durable. 35 The side margins 21, of the stand 12, are slightly depressed from the front and back toward the center. Similarly, the top margin 22, at the front and the top margin 23, at the back, have a slight dip or depression 40 from the outer ends thereof toward the center. This arrangement provides for the proper accommodation of a pen or pencil indicated by dotted lines at A in Fig. 1, because no matter in what position the pen or pencil 45 is laid on top of the stand 12, it will gravitate toward the bottle neck 11, and be sustained in position.

In the form shown in Figs. 4 and 5, my improved stand 12^a, is modified to bring 50 the lines thereof more in harmony with ink or mucilage bottles round in cross section. The rear portion of the stand, viewed in plan, is round whereas the front is ovate. The upper surface of the stand slopes down- 55 wardly and forwardly at the sides 14^a, and back 16^a, toward the elevated depression 18^a, corresponding in all respects with the depression 18, to form a seat for the lip of the inverted bottle. Similarly a projection 60 19^a, rises within the seat 18^a, and at its front side is formed with a vertical notch 20^a.

The front depression 17^a, is modified as to its outline in accordance with the general design, but presents sloping and rounded sides as in the first described construction 65 and like the first construction it has a rearwardly extending contracted terminal 17^b. The notch 20^a, forms a depression extending at the inside of the seat 18^a, and complementary to said seat and to the rearward 70 terminal 17^b. The marginal edges 21^a, slope toward the transverse center of the stand, both from the front and from the back so as to cause a pen or pencil A to gravitate toward the inverted bottle neck when sustained on the seat 18^a. The extreme front at the curvilinear angle formed by the ovate lines, is elevated as at 21^b, so that the general appearance presented by the stand 12^a, 75 is boat-like. 80

Having thus described my invention, I claim as new and desire to secure by Letters Patent:

1. A stand for use as a well for ink or mucilage, comprising a rectangular body 85 having a seat for an inverted bottle and a depression forming a well, said body having concave margins to cause a pen when laid upon any two of them to gravitate toward the seat and be arrested by the bottle. 90

2. As a new article of manufacture, a stand for use as a well for ink or mucilage, comprising a body having in its upper face two depressions of unequal depths and having the portions bounding the depressions 95 inclined upwardly and outwardly to the margin of the body, said body being provided in the shallower depression with a cylindrical projection extending above the upper face of the body and having a groove 100 opening at its lower end into the deeper depression.

3. As a new article of manufacture, a stand for use as a well for ink or mucilage, consisting of a rectangular body having in 105 its upper face two depressions of unequal depths and having the portions bounding the depressions inclined upwardly and outwardly to the edges of the body, said edges being concave, the body being provided in the shallower depression with a cylindrical projection extending above the upper face 110 of the body and having a vertical groove opening at its lower end into the deeper depression. 115

In testimony whereof I have signed my name to this specification in the presence of two subscribing witnesses.

BRONSON BARLOW.
